(57) **CLAIM**

The ornamental design for a recycle mail pack, as shown and described.

DESCRIPTION

FIG. 1 is a top perspective view of a reclosable recycle mail pack showing my new design, in a closed condition;

FIG. 2 is a top view of the recycle mail pack in an unfolded condition;

FIG. 3 is a bottom view of the recycle mail pack showing the reverse side thereof in an unfolded condition;

FIG. 4 is a right side view of an empty recycle mail pack in a partially folded condition;

FIG. 5 is a left side view of the recycle mail pack in a partially folded condition with spent bulbs inserted therein;

FIG. 6 is a perspective view of the recycle mail pack in a partially folded condition with spent bulbs therein for return to manufacturer;

FIG. 7 is a perspective view of the recycle mail pack, that is partially closed, to receive spent bulbs for mailing; and,

FIG. 8 is a perspective view of the recycle mail pack in a completely folded and closed condition for return of spent bulbs for recycling.

The broken lines showing the compact fluorescent lamps, indicia and mailing labels show the design in a condition of use and form no part of the claimed design. All other broken lines represent fold lines and form part of the claimed design.
